TRANSPARENT PROTECTIVE COVERING
AND THE LIKE

Samuel S. Miller, Chicago, Ill.

Application February 7, 1940, Serial No. 317,661

2 Claims. (Cl. 129—20)

This invention relates to transparent protective coverings and the like.

One of the objects of this invention is the provision of a protective transparent covering which is adapted for application to printed or photographic material and which serves to preserve same and enhance its appearance.

Another object of this invention is the provision of filler sheets for scrap books, loose-leaf devices and the like upon which printed or photographic material may readily be mounted without requiring the use of adhesives by the user.

A further object of this invention is the provision of filler sheets of the character above described which provide a protective transparent film for the material mounted thereon.

Other objects and advantages will become apparent during the course of the following description.

In the accompanying drawing, forming a part 20 of this specification, and in which like numerals are employed to designate like parts throughout the same:

Fig. 1 is a plan view of one form of my invention with parts turned up and broken away to 25 show the details of construction.

Fig. 2 is a bottom plan view of same.

Fig. 3 is a cross sectional view taken on line 30 3—3 of Fig. 1, and

Fig. 4 is a fragmentary cross sectional view taken on line 4—4 of Fig. 1.

Referring to the drawing, and more particularly to Figs. 1 and 2, the numeral 10 designates, generally, my improved filler sheet which comprises a sheet of transparent material 12, an intermediate separator sheet 13 and a reinforcing backing 14. The transparent sheet 12 is made preferably of cellulose acetate, Celluloid, rubberized film or any desirable transparent film. The said sheet is coated on one side, as indicated by the stippling, with a pressure sensitive adhesive which is adapted to maintain itself in a substantially moist condition until used. I have found that an adhesive formed of synthetic resins, butyl acetate and a combination of plasticizers is well suited for this purpose.

The separator sheet 13 comprises a kraft or "glassine" material having a thermoplastic coating and is arranged to lie contiguous to the adhesive surface of the sheet 12 to protect same until the filler sheet is to be used. A separator sheet 13 is incompatible with the adhesive coating of the transparent sheet 12 to enable ready separation of the separator sheet 13 and complete removal thereof. It will be understood that

the function of the separator sheet is to prevent undesired adherence of the transparent sheet 12 to the backing 14, prior to use, and also to prevent the adhesive from drying. The separator sheet 13 is removed and disposed when the filler sheet 10 is to be used.

The backing 14 may be of any suitable material, as for example, manila paper or any other desirable material and is coextensive in area with 10 that of the sheet 12. Border lines 15, 16 and 17 are printed or drawn on the backing 14 or on the sheet 12, on one or both sides thereof, and serve to frame the mounted material, thereby enhancing the appearance. The backing 14 is cut 15 on the border lines 16, along three sides, to provide a flap 18 hinged along line 19. By cutting in this fashion, the lines of separation are rendered substantially invisible. The separator sheet 13, above described, is of lesser length than the backing 14, but is substantially of the same width and is interposed between the flap 18 and the sheet 12, and extends from the bottom of the sheet 12 to the hinge line 19, as shown in Fig. 2. It will be seen that the border areas of the backing 14, outside of the lines 16 and 18, are adhesively secured to the sheet 12. By this construction the separator sheet 13 which is interposed between the sheet 12 and the hinged flap 18 and incompatible with the adhesive coating 20 on the sheet 12 can be readily separated from the sheet 12 and completely removed therefrom. Suitable holes 20 may be punched in one of the border areas to receive the fastening elements of a binder, not shown.

When it is desired to mount something, as for 35 example a newspaper clipping or a picture or advertising material on the filler sheet, the separator sheet 13 is removed, the material to be mounted is laid down on the flap 18, preferably 40 within the border lines 16, and the transparent sheet is then brought down over the said material and slight pressure is applied. It will be seen that the mounted material, as well as those 45 portions of the flap 18 which are not covered by the said material, will adhere to the sheet 12. The border area provided on the flap will adhere to the transparent sheet 12, thus forming a unitary filler sheet in which the mounted articles 50 are permanently protected against use and exposure and the appearance thereof substantially enhanced.

Because the border areas of the backing 14 are 55 covered by the transparent sheet 12, the separator sheet 13 is adhesively secured only to that portion of the transparent sheet 12 which is co-

extensive in area with that of the flap 18. The edges of the separator sheet 13 are therefore left free and provide the means by which the said sheet may be grasped when separation of the sheets is desired.

It should be noted that the mounted articles are adhesively secured to the transparent sheet 12 and not to the backing 14. Should it be desired to remove a particular article from the filler sheet, the article may be cut out without damage to itself, by cutting along the edges thereof, the said article, as it is removed, having a protective transparent film permanently secured to its surface.

From the foregoing, it is thus seen that I have 15 provided new and novel means for preserving and protecting articles of the character described and for enhancing the appearance thereof.

It is to be understood that the form of my 20 invention herewith shown and described, is to be taken as a preferred example of the same, and that various changes in the shape, size and arrangement of parts may be resorted to, without departing from the spirit of my invention or the scope of the appended claims.

I claim:

1. A sheet for the display of articles comprising a flexible, film-like sheet of material provided with a transparent pressure sensitive adhesive coating on one side thereof, said pressure sensitive coating enabling articles which are to be displayed to be adherently affixed to and bonded with said coating, said sheet being transparent so that articles so affixed will be visible 30

through and protected by said sheet, a backing, said backing being cut to provide a hinged flap and a border area around all sides thereof, said film-like sheet permanently adhering to said backing along the border area, a separator sheet interposed between said film-like sheet and said hinged flap and being incompatible with the adhesive coating to enable ready separation and complete removal of said separator sheet from said film-like sheet to permit the article to be permanently adhered to said film-like sheet between said sheet and said hinged flap and said film-like sheet being permanently adherable to said hinged flap.

2. A sheet for the display of articles comprising a flexible, film-like sheet of material provided with a transparent pressure sensitive adhesive coating on one side thereof, said pressure sensitive coating enabling articles which are to be displayed to be adherently affixed to and bonded with said coating, said sheet being transparent so that articles so affixed will be visible through and protected by said sheet, a border member to which the outer portions of the film-like sheet is permanently secured, a backing flap, a separator sheet interposed between said film-like sheet and the backing flap and being incompatible with the adhesive coating to enable ready separation and complete removal of said separator sheet from the film-like sheet to permit the article to be permanently adhered to said film-like sheet between said sheet and said flap and said film-like sheet being permanently adherable to said backing flap.

SAMUEL S. MILLER.
